FRICTION SAW FOR CUTTING OFF METAL OR THE LIKE

Walter Grabes, Houston, Tex.
(P.O. Box 895, Bellaire, Tex. 77401)

Filed Sept. 26, 1968, Ser. No. 13,721

Term of patent 14 years

Int. Cl. D15—05

U.S. Cl. D93—3

FIG. 3.

FIG. 4.

FIGURE 1 is a front perspective view of a friction saw for cutting off metal or the like embodying my new design, and

FIG. 2 is a top plan view,

FIG. 3 is a rear elevational view, and

FIG. 4 is an end elevational view thereof.

I claim:

The ornamental design for a friction saw for cutting off metal or the like, substantially as shown.
